UNITED STATES PATENT OFFICE.

CARL RUDOLPH SCHULTZ, OF NEW YORK, N. Y.

BOTTLE-CAP.

1,145,805.

Specification of Letters Patent.

Patented July 6, 1915.

Application filed February 19, 1915. Serial No. 9,270.

To all whom it may concern:

Be it known that I, CARL RUDOLPH SCHULTZ, a citizen of the United States, and a resident of the city of New York, borough 5 of Manhattan, in the county and State of New York, have invented a new and Improved Bottle-Cap, of which the following is a full, clear, and exact description.

Among the principal objects which the 10 present invention has in view are: to provide means for reinforcing the body of a bottle adjacent the neck portion thereof; to provide an inscription plate and means for holding the same rigidly in position on the 15 body of a bottle; and to provide a light metal cover for protecting a bottle structure adjacent the neck thereof.

Drawings.—Figure 1 is a side view of a bottle having a cap attached thereto constructed and arranged in accordance with the present invention, a portion of said cap being shown in section to disclose the interior structure thereof; Fig. 2 is a perspective view in detail, of a cover plate for protecting the weaker portion of the bottle structure; Fig. 3 is a detail view showing a contracting ring for anchoring the covering plate in service position.

Description.—As seen in the drawings, 30 the bottle 8 is of conventional pattern, and is provided with a lip 9. For surrounding the neck of the bottle, and below the lip 9, a split, screw-threaded collar 10 is provided. The collar 10 is divided to form a space between the end walls 11. Below the screw-threaded portion of the collar 10, said collar is extended to form an annular lip 12, the inner surface of which is recessed to form a curved wall 13, which corresponds with the 35 neck 14 of a cover plate 15. The cover plate 15 is cupped to provide an inclined wall terminating at the outer edge thereof in an annular cylindrical wall 16. The plate 15 is made preferably from light metal. The 40 form to which it is pressed gives sufficient strength to the cover to prevent the same becoming marred in service, and to provide a protective member extending over an enlarged area of the bottle structure to dis- 45 tribute any strain or shock on the neck of the bottle, imparted thereto when the collar 10 or dispensing device, such as the draw-off cock 17 connected therewith, is struck. The 50

exposed surface of the cover may be utilized for having imparted thereto any suitable 55 inscription or ornamentation directing the consumer as to the disposition of the bottle, or to augment the pleasing appearance thereof.

The cock 17 or other dispensing member 60 with which bottles of this character are provided, has a threaded cap nut portion 18. The portion 18 is slightly tapered inward, so that when screwed upon the collar 10, said collar is gradually compressed or reduced in diameter and forced upon the neck of the bottle and the neck 14 of the cover plate 15 which is infolded by said collar 10 and the lip 12 thereof. When the cock 17 is screwed firmly upon the collar 10, it will be 70 found, the curved inner surface of the lip 12 grips the neck 14 and presses down the plate 15 to rest firmly on the bottle 8. When, now, any blow or strain is imparted to the cock 17 or fixture connected with the 75 collar 10, it is transferred or distributed to the plate 15 and to the annular wall 16 thereof. The wall 16 being spread to enclose an extended area, the force or impact of the strain is dissipated in proportion to 80 the extent of the area.

Claims:

1. A bottle cap comprising a cover plate having a cup-shaped body provided with a contracted neck and an enlarged annular 85 rim, the wall of said neck being inclined upwardly and inwardly; a contractible collar having a lip for surrounding said neck to grip the same; and means for contracting said collar in service. 90

2. A bottle cap comprising a cover plate having a cup-shaped body provided with a contracted neck and an enlarged annular rim, the wall of said neck being inclined upwardly and inwardly; a contractible collar 95 having a lip for surrounding said neck to grip the same; and means for contracting said collar to grip the neck of said cover plate and to force the annular rim thereof to bear upon the bottle structure to which said 100 plate is applied.

3. A bottle cap comprising a cover plate having a cup-like body embodying a contracted neck opening, the outer walls whereof are inclined, and a relatively extended, 105 cylindrical bottom rim; a contractible collar

having a screw-threaded portion and a bottom-opening recess, the inner walls of said recess corresponding with the outer walls of the neck portion of said cover plate; and
5 a cap nut infolding said collar, the walls of said nut being tapered to contract said collar.

In testimony whereof I have signed my name to this specification in the presence of two subscribing witnesses.

CARL RUDOLPH SCHULTZ.
